DESIGN FOR A GLOVE

Charles R. Kovar, Richmond Hill, N. Y.

Application November 14, 1935, Serial No. 59,542

Term of patent 3½ years

To all whom it may concern:

Be it known that I, Charles R. Kovar, a citizen of the United States, residing at 102-32 Park Lane South, Richmond Hill, Long Island, in the city of New York, county of Queens, and State of New York, have invented a new, original, and ornamental Design for a Glove, of which the following is a specification, reference being had to the accompanying drawing, forming part thereof.

Figures 1 and 2 of the drawing are respectively front and back views of a glove showing my new design.

The entire exposed surface of the glove is covered with parallel ribs formed in the knitted fab-

ric of which the glove is made and arranged transversely of the length of the glove, except on the back of the cuff where these ribs run diagonally of the length of the glove. The design is further characterized by a symmetrical flaring cuff slightly indented on the front and deeply indented on the back of the glove; the cuff, having thereon lines of stitches radiating from the base of the deep indentation as shown in the drawing.

I claim:

The ornamental design for a glove, as shown and described.

CHARLES R. KOVAR.
